UNITED STATES PATENT OFFICE.

MASAJI YOKOYAMA, OF SETAGAYA-MURA, JAPAN.

ELECTRICALLY-OPERATED AUTOMATIC WINDING DEVICE.

Application filed January 30, 1926, Serial No. 85,060, and in Japan January 31, 1925.

This invention relates to improvements in winding apparatus for spring motors, and aims to provide a device which may employ electric current supplied by a city line to 5 maintain the spring motor continuously running, even though the current from the supply line be temporarily cut off.

The invention is particularly applicable to maintain continuous operation of clock 10 mechanisms without the attendant danger of faulty operation thereof due to the winding action of the clock spring by the electric motor and the simultaneous unwinding action of said spring operating the clock.

15 The invention further aims to provide a clock winding apparatus in which the time at which the winding operation commences can be chosen at will.

20 The invention also aims to provide a winding apparatus which can be adapted to any type of clocks already in existence, by simply applying the apparatus on to the barrel arbor.

25 The invention is also applicable to large clocks of a special construction, such as gravity-operated ones, also to winding of electric time-switches, to scientific machinery for replenishing power thereof, in which a reciprocal oscillating motions are caused to 30 take place at a definite period, and to winding phonographs and to other similar purposes.

In the drawing annexed herewith, Figure 1 represents a front view of a clock mechanism provided with the winding device according to this invention.

Figure 2 is a plan view thereof.

Figure 3 is a plan view partly in cross-section of the differential transmission gear 40 connected with the primary slip ring.

Figure 4 is a transverse section thereof taken on the line 4—4 of Fig. 3.

Figures 5 to 8 represent various positions of the two co-operating slip rings.

45 Now referring more particularly to the characters and numerals on the drawing, 1 is a barrel for housing the main spring for storing the motive power and driving the clock mechanism W (diagrammatically represented on the drawing). The inner end of this spring is fixed to the arbor A, and its outer end to the inner side of the barrel 1, as usual. This spring, on one hand, is wound up by an electric motor 6, say once 55 in every 24 hours, through the speed reducing gears 7, 8, 9, 10, 11, and 18, and, on the

other hand, drives the clock mechanism W through the gears 2 and 3, the first named gear 2 being rigidly attached to the barrel 1. The gear 2 also drives continuously and slowly, by the unwinding of the main spring, the primary slip ring 15, in the direction shown by the arrow E¹, through the gears 12 and 13 and the differential transmission gear D, which will be more fully explained hereinafter. In this wise, the primary slip ring 15 is driven continuously, performing one complete revolution in 48 hours, or one half revolution in every 24 hours.

When the motor 6 is rotated, as explained below, the gear 18 which is mounted upon the arbor A will be driven. The rotation of this gear is transmitted to the gear 19, and then to the shaft 20. The rotation of this shaft will cause, at one hand, the secondary slip ring 16 to rotate in the direction shown by the arrow E², and, at the other hand, cause simultaneous rotation of the primary slip ring 15 in the direction of the arrow E¹, through the intermediate gears 22, 23, 24 and the differential gear D.

By means of this gearing D, the primary slip ring 15 is connected at one side with the clock operating main spring and at the other side with the winding motor 6, the whole gearing of transmission being housed in a cylindrical casing constituting the primary slip ring 15.

As the mainspring unwinds, it drives on one hand the clock mechanism W and on the other hand drives slowly and continuously the sun wheel 14 through the pinions 12 and 13. The pinion 13 is rigidly mounted upon the hub of the sun wheel 14 and the cylindrical drum 15 constituting the primary slip ring is freely rotatable upon the hub of the sun wheel 14. On the other side of the drum, the motion of the motor 6 is transmitted, through the intermediate gears 23 and 24, to another sun wheel 17, which is rigid with the pinion 24 and is provided on the other side in the interior of the drum 15. The drum 15 is also loosely mounted upon the hub of this sun wheel 17. Two sun wheels 14 and 17 gear with two sets of planet wheels 27, 28 and 29, 30, rotatably provided upon the shafts mounted on the side walls of the drum and symmetrically situated so as to balance the torsional moments.

By a suitable proportioning of the sizes of

- the gears 22, 23 and 24, the secondary slip ring 16 may be made to complete one revolution while the primary slip ring 15 completes one half revolution. The length of time required for the winding up of the main spring, which operation may conveniently be performed by the electric motor 6 once in 24 hours, does not exceed a few minutes at the most, although it may vary according to the type of the clock mechanism. The primary slip ring 15 which is slowly driven by the unwinding of the main spring, so as to complete one revolution in very 48 hours, is constituted of the metallic portion 15^a and the insulating portion 15^b, each covering one half circumference. Exactly speaking, however, the length of the metallic portion 15^a should be short of 180 degrees by the width of the sliding brushes 25, 25. The secondary slip ring 16, which is rotated only when the motor 6 is operated consists of a broad metallic portion 16^a extending nearly the whole of the circumference and a narrow insulating portion 16^b. Theoretically, the insulating portion 16^b may be of a length barely sufficient to insulate the two brushes 26, 26 from each other, but should better be made broader, to a certain extent, in consideration of the plays of the gearings. The brushes 25, 25, and 26, 26 should be arranged so as to lie in the axial direction of the respective slip rings.
- In this device, the motion due to the unwinding of the main spring is transmitted to the sun wheel 14, which motion is transmitted to the planet wheels 27, 28 and 29, 30. When these planet wheels tend to rotate upon their respective axes, they are prevented from doing so by reason of the other sun wheel 17 possessing a large resistance, to be driven from this side, due to a train of gearings connected thereto. Consequently, the drum 15 constituting the primary slip ring will rotate as a whole round the sun-wheels at one half speed, together with the planet wheels. When the brushes 25, 25 are electrically connected by coming into contact with the metallic portion 15^a, the motor 6 will start and will drive the drum 15 by means of the other sun wheel 17. In this instance, the speed of the drum 15 will be equal to the difference between the speeds caused from the two opposite sides. On account of the fact that the speed of the drum due to unwinding of the spring is negligible in comparison with that due to the rotation of the motor, the speed of the drum 15 is practically equal to one half of that of the sun wheel 17.
- In case the diameters of the two sun wheels are equal and also those of the planet wheels are mutually equal, one revolution of any one of the sun wheels is transmitted as half a revolution of the drum 15. However, any ratio of the speeds may be obtained by a

suitable choice of diameters of these wheels, thus enabling to keep for reserve any length of time for interruption of electrical power supply.

The direction of the rotation of the primary slip ring 15 caused by the unwinding of the spring need not necessarily be same as that due to the operation of the winding motor.

When the primary slip ring 15 is rotated slowly in the direction indicated by the arrow E¹ due to gradual unwinding of the main spring as the time goes on, and when the pair of brushes 25, 25 fall on the metallic portion 15^a (position of Figure 5), these brushes will be electrically connected and the circuit of the electric motor 6 will be completed at this point, as clearly shown in Figure 5. Thus the motor will be driven by the power derived from the source of electricity, for example, city power lines. When the motor is started, both the slip rings 15 and 16 revolve rapidly in the direction shown by the arrows, and come to the positions shown in Figure 6. In this position, both pairs of brushes 25, 25 and 26, 26 fall on the respective insulating portions, and the circuit of the electric motor being broken, the motor comes to rest. In this manner, the main spring is wound up for 24 hours. The secondary slip ring 16 comes to the same initial position, and will not be driven by the motor 6 unless after the lapse of 24 hours, when, the primary slip ring 15 again comes to the position shown in Figure 5.

Now, suppose that, when the slowly and constantly revolving slip ring 15 came to the position shown in Figure 5, there was an interruption in the supply of power in the city main, the motor will not start even though its circuit be completed at the brushes 25, 25. Therefore, the secondary slip ring 16 will not be driven. But the primary slip ring 15 will continue its usual slow rotation as far as the main spring has its stored energy in reserve. When the interruption of the power supply ceases, say, after four continuous hours, the primary slip ring will have rotated one-twelfth of a revolution and will be at a position shown in Figure 7. In this position, the brushes 25, 25 will still lie on the metallic portion and will be electrically connected, so that the motor 6 re-assumes its rotation, driving the two slip rings simultaneously. When the first slip ring 15 has rotated $\frac{1}{12}$ of its circumference, the brushes 25, 25 slide off the metallic portion and fall on the insulating portion 15^b. However, the brushes 26, 26 on the secondary slip ring, being still on the metallic portion thereof, both of the slip rings will continue their rotations and will come to rest only after the primary slip ring has rotated 180 degrees and the secondary slip ring 360 degrees. In this manner, the main spring is wound for com-

plete 24 hours. This position is shown in Figure 8. In this instance, the primary slip ring is in a position advanced by 4 hours. However, the brushes 25, 25 will come to contact with the metallic portion 15^a as early as after 20 hours, or after a duration of time of 24 hours less by the interval of time of interruption of power, when, the slip rings come to the position of Figure 5, 10 and the whole system will be brought back to the initial regular positions.

In the above, it has been assumed that the main spring is wound once in every 24 hours, but this period is arbitrary and can be varied 15 at will by a suitable choice of the sizes of the gearings. Also, the reserve of power pre-determined for the capacity of the main spring can be assigned at will.

In each instance above mentioned, the time 20 of commencement of the winding operation may be varied at will by simply adjusting the mounting of the slip rings, on the respective spindles.

What I claim is:

- 25 1. A winding device for a spring motor operable by an electric motor, comprising a differential gearing, the housing of which is provided with electrical conducting and insulating portions, an electric motor, brushes 30 engaging said housing adapted to close the circuit through the electric motor, and said differential gearing being mechanically connected to both the spring motor and the electric motor.
- 35 2. A winding device for a spring motor operable by an electric motor, comprising a differential gearing, the housing of which is provided with electrical conducting and insulating portions, an electric motor, 40 brushes engaging said housing adapted to close the circuit through the electric motor, and said differential gearing comprising a planetary gear train having two sun wheels, one of which is connected to the spring motor, and the other connected to the electric motor.
- 45 3. A winding device for a spring motor operable by an electric motor, comprising a differential gearing, the housing of which 50 is provided with electrical conducting and insulating portions, an electric motor, brushes engaging said housing adapted to close the circuit through the electric motor, and said differential gearing comprising a 55 planetary gear train having two sun wheels, each of which has a pair of planet wheels situated and maintained upon shafts within the housing, the planet wheels of the respective sun wheels being in meshing engagement, 60 one of said sun wheels being connected to

the spring motor, and the other to the electric motor.

4. A winding device for a spring motor operable by an electric motor, comprising a differential gearing, the housing of which is 65 provided with electrical conducting and insulating portions, an electric motor, brushes engaging said housing adapted to close the circuit through the electric motor, and said differential gearing being mechanically connected to both the spring motor and the electric motor in such manner that motion communicated to one side of the differential by the spring motor is not communicated to the other side of the differential, and vice versa. 70

5. A winding device for a spring motor operable by an electric motor, comprising a pair of slip rings each provided with electrical conducting and insulating portions, an electric motor, and a pair of brushes 80 engaging each slip ring adapted to close the circuit through the electric motor, said pairs of brushes being connected to the electric motor in parallel.

6. A winding device for a spring motor 85 operable by an electric motor, comprising a pair of slip rings each provided with electrical conducting and insulating portions, an electric motor, and a pair of brushes engaging each slip ring adapted to close the circuit 90 through the electric motor, said pairs of brushes being connected to the electric motor in parallel, the conducting and insulating portions of one slip ring being substantially of equal lengths, the insulating portion of 95 the other slip ring being of barely sufficient length to provide an open circuit for the pair of brushes in contact with said slip ring.

7. A winding device for a spring motor operable by an electric motor, comprising 100 a pair of slip rings each provided with electrical conducting and insulating portions, an electric motor, and a pair of brushes engaging each slip ring adapted to close the circuit through the electric motor, said pairs 105 of brushes being connected to the electric motor in parallel, gearing connections between said electric motor and both slip rings, between said electric motor and said spring motor, and between said spring motor and 110 one of the slip rings, said gearing being such that upon the short-circuiting of a pair of brushes by the conducting portion of the first slip ring, the motor will operate to rotate both slip rings until the insulated portions thereon come into contact with their respective pairs of brushes. 115

In testimony whereof I affix my signature.

MASAJI YOKOYAMA.
